US00D679763S

(12) **United States Design Patent**
Mimlitch, III et al.

(10) **Patent No.:** **US D679,763 S**
(45) **Date of Patent:** **** Apr. 9, 2013**

(54) **ROBOTIC TOY CAR**

(75) Inventors: **Robert H. Mimlitch, III**, Rowlett, TX (US); **David A. Norman**, Greenville, TX (US); **Raul Olivera**, Greenville, TX (US); **Douglas Michael Galletti**, Allen, TX (US); **James Anthony Trzaskos**, Massena, NY (US)

(73) Assignee: **Innovation First, Inc.**, Greenville, TX (US)

(**) Term: **14 Years**

(21) Appl. No.: **29/418,208**

(22) Filed: **Apr. 13, 2012**

(57) CLAIM

The ornamental design for a robotic toy car, as shown and described.

DESCRIPTION

FIG. 1 is a top perspective view showing a first embodiment of the robotic toy car;

FIG. 2 is a bottom perspective view of FIG. 1;

FIG. 3 is a top side view of FIG. 1;

FIG. 4 is a bottom side view of FIG. 1;

FIG. 5 is a front side view of FIG. 1;

FIG. 6 is a back side view of FIG. 1;

FIG. 7 is a right side view of FIGS. 1; and,

FIG. 8 is a left side view of FIG. 1.

The broken lines are for the purpose of illustrating portions of the environmental structure and forms no part of the claimed embodiment and design.

1 Claim, 7 Drawing Sheets
